UNITED STATES PATENT OFFICE.

GEORGE M. HATHAWAY, OF NEW YORK, N. Y.

CIGAR-WRAPPER-ROLLING MACHINE.

SPECIFICATION forming part of Letters Patent No. 424,296, dated March 25, 1890.

Application filed February 25, 1889. Serial No. 301,078. (No model.)

To all whom it may concern:

Be it known that I, GEORGE M. HATHAWAY, a citizen of the United States, residing at New York, county of New York, State of New York, have invented certain new and useful Improvements in Cigar-Wrapper-Rolling Machines, of which the following is so full, clear, and exact a description as will enable others skilled in the art to which my invention appertains to make and use the same, reference being had to the accompanying drawings, in which—

Figure 1 is a side elevation of my improved machine. Fig. 2 is a vertical section of the same. Fig. 3 is a detail view of the mechanism for adjusting the belt, as will be herein-after fully explained. Fig. 4 is a detail perspective of the removable plate A⁴. Fig. 5 is a detail end view of the upper portion of the wrapper-rolling machine.

The object of my invention is to provide a cigar-wrapping machine by the use of which an operator can wrap the greatest number of cigars with the greatest degree of accuracy, with the least liability of destroying the wrapper and cigar, and do it all in the shortest possible time with the least expense of physical and mechanical force.

Another object of my invention is to construct a cigar-wrapper-rolling machine by the use of which the operator can stand at either side of the machine and wrap a cigar with the same ease and facility.

Another object of my invention is to provide a cigar-wrapper-rolling machine which will press with equal and uniform tension against all parts of cigars of various shapes.

The objects generally of my device are to produce a cigar-wrapper-rolling machine which will be simple in construction, efficient in operation, and one which can be readily understood and operated to advantage by those not particularly skilled in the art, and one which, by reason of its simplicity and cheapness, will be within the reach of the most unpretending manufacturer.

In the accompanying drawings, A designates a bed-plate, which is adapted to be secured to a table or bench by means of screws or bolts, which may be inserted through perforations a a in the plate A. This bed-plate

A is provided with a hollow rib or ridge A', through which is adapted to slide longitudinally an adjustable stop a'. This adjustable stop is adapted to be slid longitudinally to fit 55 cigars of varying lengths, and it is locked in position by a set-screw or stop a². The bed-plate A is also provided with a central perforation A², above which is situated a continuous belt B, and below which is located a second continuous belt C. These belts are adapted to move at this point in opposite directions and on opposite sides of the perforation A² in the bed-plate.

The bed-plate A is perforated, as shown in 65 dotted lines at a³ a³, and through these perforations extend two vertical rods b b, to the upper ends of which is secured a yoke D, the upper central portion of which, together with a longitudinal hollow casing D², forms a journal-bearing for a shaft E, on one end of which is secured a cog-wheel F, and to the opposite end of which is secured a serrated or corrugated drum G, which rotates within the casing H. The lower ends of the casing H are 70 provided with inverted-U-shaped slots, below each side of which extend two fingers c c, and on the outer ends of which are provided stops or lugs c² c².

Sliding within the recesses between the fingers c c are two bolts d d, provided with set-screws d² d². The inner ends of these bolts d d are provided with washers d³, and on these bolts d d are loosely mounted arms e e, to the lower ends of which are secured rollers i i, 80 which rollers are journaled between the lower ends of the arms e e and are held in place by extending through perforations f f in the lower outer ends of the arms e e. It will be readily understood that the main portion of 85 the rollers i i is somewhat larger than the arbors j j, and this will prevent accidental longitudinal displacement of the rollers. The bed-plate A is also provided on its lower side and at the end beyond the perforations a a 90 with a hanger I, in which is journaled one end of the shaft J, and through which extend the vertical rods b b below the line of the shaft J.

The shaft J is provided with two grooved 100 pulleys K, which are adapted to receive a belt K', through the medium of which motion is

imparted to the entire device. The outer end of the shaft J is provided with a cog-wheel L, which meshes with the intermediate cog-wheel M, the purpose of which will be hereinafter explained.

Between the central portions of the bed-plate A are a pair of hangers N N, in which is journaled the inner portion of the shaft J, and between which hangers rotates the corrugated drum O, which imparts rotary motion to the continuous belt C.

Somewhat above the drum O, and between it and one of the rollers r, is situated a tension-roller s, which is journaled in the inner ends of a pair of eyebolts t t, which eyebolts are curved and extend through curved perforations u u in the hangers N. The springs v v serve to keep the tension-roller s constantly in contact with the belt C, as is clearly shown in Fig. 2. The rollers r r are journaled in hangers r' r' beneath the bed-plate.

The vertical rods b b are provided with coiled springs h' h', the ends of which impinge against the ends o o of the hanger I and the ends of the cross-bar P, respectively. The cross-bar P is perforated at p p, and through these perforations extend the lower ends of the vertical rods b b, and the cross-bar P is held in position against displacement by nuts q q. The central portion of this cross-bar P is provided with a knee-socket Q, which is vertically adjustable by means of the screw-threaded bolt R, and is adapted to be locked in position by the set-nut S, as will be readily understood by reference to Fig. 2.

On each side of the central opening A², I provide removable plates A⁴ A⁴, which are adapted to be removed and interchanged, and which are held in position by set-screws a⁵ a⁵. These plates may be changed and varied at will to accommodate cigars of various sizes and shapes.

By reference to Fig. 2 it will be observed that the knee-socket Q is rigidly connected with the vertically-reciprocating rods b b', to the upper ends of which is connected the shaft E, to which are secured the cog-wheel F and the casing H, which latter contains and supports the upper portion of the wrapper-rolling mechanism; hence by raising the socket Q with the knee the wheel F will be elevated a sufficient distance to clear the intermediate cog-wheel M, and the casing H, together with its belt and adjusting mechanism, will be raised a sufficient distance to enable the operator to remove and replace the cigar T. The depth to which the casing H and its belt B will descend, or, in other words, the distance between the lower working-face of the belt B and the upper working-face of the belt C, will be adjusted and determined by means of a set-screw V, which extends up between the rods b b and is secured to the bed-plate A, as is clearly shown in Fig. 1.

From the nature of the case it will be readily understood that motion imparted to the grooved pulley or pulleys K will rotate these

pulleys and the shaft J and the drum O and the cog-wheel L in one direction, and will rotate the intermediate cog-wheel M in an opposite direction. This wheel M, meshing with the wheel F, will also rotate the latter in the same direction with the cog-wheel L, and through the medium of the intermediate connections will impart rotary motion to the belt B in the same direction with the motion imparted to the continuous belt C. Thus we have the lower belt advancing in one direction with its upper surface moving across the opening A² in the bed-plate A, and the upper belt advancing in the same direction with its lower surface moving across the line of the opening A² in an opposite direction. By this means a substantially stationary rotary motion will be imparted to a cigar when one is placed between the two operating-surfaces of the belts, and the operator can so hold a wrapper that it will wrap a cigar with great evenness and precision.

The varying sizes and shapes of cigars will be readily accommodated and held in position by the adjustable steadyng-clamp U, which is vertically adjustable through the medium of the set-screw d², which serves to facilitate the adjustment of the outer pair of the arms e e, as will be clearly seen in Fig. 1.

The operation of my device is as follows: The proper plates having been selected, and the steadyng-clamp U having been adjusted to accommodate the size and shape of the cigar, the adjustable stop a' having been secured in the proper position to accommodate the length of cigar to be operated upon, a cigar T is placed in position between the two oppositely-moving surfaces of the upper and lower belts, the upward pressure of the knee on the socket Q is removed, and the resiliency of the springs h' h' will force the rods b b, and through them the upper cog-wheel F and the casing H, down until the two oppositely-moving surfaces of the belts B and C are both in contact with the cigar. Rotary motion is then imparted to the shaft J and the wrapper is held in the proper position to wrap the cigar, when pressure is applied to the under side of the socket Q and it and the casing H and the intermediate mechanism are raised, when the cigar may be removed and the process repeated.

I do not wish to be understood as claiming this device broadly as against different construction to accomplish the result. (See my application filed May 28, 1889, Serial No. 312,382, in this connection.)

Having now described the objects, uses, and advantages of my invention, and having set forth a preferred construction, what I believe to be new and desire to secure by Letters Patent, and what I therefore claim, is—

1. In a cigar-wrapper-rolling machine, two traveling belts having their opposing surfaces moving in opposite directions and located one above the other a sufficient distance apart to accommodate and impinge against a cigar, in

combination with shafts J and E, the said shaft E supporting the upper of said traveling belts, vertical rods *b b*, having a yoke D, in which the shaft E is journaled, connecting 5 their upper ends, and a cross-bar P, connecting their lower ends, a knee-socket connected to said cross-bar P, coiled springs encircling the vertical rods *b b*, means for imparting motion to shafts J and E, and means for holding distended the adjacent surfaces of said belts.

2. In a cigar-wrapper-rolling machine, an apertured bed-plate, in combination with shafts J and E, journaled, respectively, beneath and 15 above said bed-plate, the said shaft E having a casing at one end, the said casing being formed with inverted-U-shaped slots near its lower end, bolts vertically adjustable within said slots and provided with screws, diverging arms loosely mounted on said bolts and carrying rollers *i i* at their lower ends, rollers *r r*, journaled beneath the bed-plate, belts B and C, having their opposing surfaces moving 20 in opposite directions, the said belts respectively engaging the rollers *i i* and *r r*, as shown, whereby a seat for the cigar is formed between said rollers, and means for imparting motion to said belts, all arranged substantially as shown, and for the purposes set 25 forth.

3. In a cigar-wrapper-rolling mechanism, an apertured bed-plate, shafts J and E, journaled, respectively, beneath and above said bed-plate, a casing H at one end of shaft E, 30 two endless traveling belts located one above the other adjacent to the aperture in the bed-plate and having their opposing surfaces moving in opposite directions, and means for

holding distended the opposing surfaces of said belts, the upper of said belts being partially inclosed by said casing H, the means for holding its lower end distended being also supported by said casing, in combination with gear-wheels mounted on adjacent ends of the shafts J and E, an idler located between said 40 gear-wheels and intermeshing therewith, rods *b b*, a yoke connecting the upper ends of said rods and supporting the shaft E, a cross-bar connecting the lower ends of said rods, coil-springs encircling said rods, a knee-socket 45 connected with the cross-bar, and means for imparting motion to shaft J, all substantially as shown and described.

4. In a cigar-wrapper-rolling machine, an apertured bed-plate, a vertically-adjustable 50 horizontal shaft journaled in a bearing above said bed-plate, and a casing carried on the end of said shaft, said casing having slots, in combination with a bolt adjustable within the slots in said casing and provided with 55 screws, diverging arms loosely mounted on said bolt and having rollers *i i* at their lower ends, rollers *r r*, journaled beneath the bed-plate, belts B and C, having their opposing surfaces moving in opposite directions, the 60 said belts being carried and distended by the rollers *i i* and *r r*, respectively, whereby a seat for the cigar is formed between said rollers, and means for imparting motion to said belts.

In testimony whereof I affix my signature 70 in the presence of two witnesses.

GEORGE M. HATHAWAY.
